(57) **CLAIM**

The ornamental design for an archery inclinometer, as shown and described.

DESCRIPTION

FIG. 1 is a front perspective view of an archery inclinometer showing our new design;

FIG. 2 is a top view thereof;

FIG. 3 is a bottom view thereof;

FIG. 4 is a left side view thereof, the right side view being a mirror image thereof;

FIG. 5 is a front thereof;

FIG. 6 is a rear view thereof; and,

FIG. 7 is a perspective view showing the archery inclinometer in the environment in which it is to be used.

The broken line showing in FIG. 7 is included for the purpose of illustrating environment and forms no part of the claimed design.
